UNITED STATES PATENT OFFICE.

CHARLES A. HORN, OF NEW YORK, N. Y., ASSIGNOR OF ONE-FOURTH TO W. EVERETT RUNDLE, OF EAST ORANGE, NEW JERSEY, AND ONE-FOURTH TO HAROLD E. LOMBARD, OF BLOOMFIELD, NEW JERSEY.

AUTOMATIC FURNACE-GRAVE.

1,271,710.

Specification of Letters Patent. Patented July 9, 1918.

Application filed June 2, 1917. Serial No. 172,416.

To all whom it may concern:

Be it known that I, CHARLES A. HORN, a subject of the German Emperor, residing at Woodhaven, in the borough and county of 5 Queens, city and State of New York, have invented certain new and useful Improvements in Automatic Furnace-Grates, of which the following is a full, clear, and exact description.

10 This invention relates to furnace grates, and its chief object is to provide a grate adapted to burn any and all kinds and grades of coal, bituminous or anthracite, at will. Another object is to provide a self-stoking 15 grate capable of stoking the fuel over the surface of the grate in an effective manner, and, if desired, at a rate diminishing from front to back for the purpose of keeping the thickness of the bed of fuel more 20 nearly uniform or with such distribution of thickness as will conduce to most efficient utilization of the fuel and the air-supply. Another object is to provide a furnace grate in which the air-supply and the distribution 25 thereof over the grate can be varied as desired, so as to give, for example, a uniform distribution throughout, or to give a non-uniform distribution, with more air at one point than another; in short, practically 30 any distribution and rate that may be best or most desirable, according to circumstances. Another object is to provide an automatic grate which will discharge the ash, clinkers, and other refuse, without the 35 use of water-backs and special dump-plates or the like. Still another object is to provide an automatic grate which will agitate the fuel bed, thereby facilitating the passage 40 of air and preventing the formation of a cinder-crust, which latter, as is well known, is apt to confine the heat to such an extent as to cause injury to the grate-tops. To 45 these and other ends the invention consists in the novel features of construction and combinations of elements hereinafter described.

In carrying out the invention in the preferred manner I provide a series of parallel rock shafts extending across the grate area, 50 the series being inclined downwardly at a suitable angle from front to back, that is, from the intake end of the grate to the rear

or discharge end. Each rockshaft carries a carrier-bar (on which the grate-tops are mounted) and each bar is so arranged as to 55 lie normally over the rockshaft immediately in front. Each rockshaft also carries one or more devices which, when the shafts are rocked in the proper direction, can lift the superposed carrier-bars and move the same 60 toward the rear, thereby raising the fuel bed and moving it to the rear. The mechanism for rocking the shafts is constructed to cause the carrier-bars (and, of course, the grate-tops thereon) to return to normal position 65 in succession, from front to rear. That is, the carrier-bar at the front first swings back, then the second from the front, and so on. By this method the fuel bed is not permitted to fall back, bodily, to or nearly to, its 70 former position. Instead, the grate-tops slip back under the fuel, leaving the entire bed in practically the position to which it was moved by the simultaneous movement of the grate-tops. In short, the grate-tops 75 return to home position like a receding wave from front to rear. As the wave travels a like wave traverses the fuel bed, thereby agitating the fuel and breaking up the bed more or less. At the rear of the grate the 80 described rearward movement of the fuel bed projects its rear portion, composed of ash and other refuse, over the edge of the ashpit, thus permitting the refuse to fall into the latter. Means are also provided by 85 which the stroke or extent of movement of any carrier-bar or bars can be varied. For example, the stroke may diminish from front to rear, so that the fuel-travel will be less rapid at the back. In this way it is 90 easy to thicken the fuel bed toward the rear of the grate, to compensate for the consumption of the fuel; it being readily understood that with a uniform travel the amount of unconsumed fuel at the rear would be much 95 less than at the front.

The embodiment thus briefly outlined is illustrated in the annexed drawings, in which—

Figure 1 is a vertical longitudinal section 100 on the plane of line 1—1 in Fig. 2, looking in the direction of the arrows.

Fig. 2 is a plan view of the grate, with parts broken away and with most of the

grate-tops removed to show the underlying parts.

Fig. 3 is a front view of the furnace, showing the external parts of the grate-operating mechanism.

Fig. 4 is a detail plan view, showing portions of several grate-top carrier-bars and such parts of the actuating mechanism as are immediately connected therewith. This figure also shows a number of the grate-tops 10 in place on their respective carrier-bars.

Fig. 5 is a detail section illustrating the movement of the carrier-bars and the grate tops thereon.

Fig. 6 is a detail view of one form of device for differentiating the throw of the carrier-bars, for example giving the rear carrier-bars less throw than those at the front.

Fig. 7 is a detail sectional view, on the same plane as Fig. 1, illustrating the function of the means for determining the differential throw of the carriage-bars.

Fig. 8 is a detail cross section of several 25 grate-tops, on the plane indicated by the line 8 in Fig. 5, illustrating the method of spacing the grate-tops apart for the passage of air between them to the fuel above. In this figure the air-spaces are of uniform width.

Fig. 9 is a detail cross section similar to Fig. 8 but showing air-spaces successively wider from left to right, thereby admitting more air to the fuel at one end of the series of grate-tops than at the other.

Fig. 10 is a detail cross section on the plane indicated by line 10 in Fig. 5.

Fig. 11 is a detail perspective view of one of the spacers or spacing saddles used between the grate-tops to space the same apart 40 on the carrier-bars.

Fig. 12 is a detailed plan view of one end of the sliding grid-valve or gate used in the bottom of the fuel hopper.

Referring to the drawings, chiefly Fig. 1, 45 10 designates the fire or combustion chamber of the furnace, having a roof 11 and at its front, just below the roof, a mouth 12 for the introduction of fuel. The fuel is supplied from a hopper 13 extending across the 50 combustion chamber above the mouth. The hopper may be divided into several compartments by walls 14 which, being integral with or firmly connected to the vertical rear wall and inclined front wall of the hopper, 55 aid the latter wall in resisting outwardly or downwardly exerted stresses, as do also the fins 15 on the outside. The bottom of the hopper is formed with a plurality of parallel slots 16 extending longitudinally of 60 the furnace, and above the hopper bottom is a transversely sliding grid 17 (Fig. 12) having similar slots 18. When the grid slots, 65 are in registry with the hopper slots 16 the fuel can pass downwardly upon the horizontal guide-plate 19. The grid is provided

at one end with an actuating bar 20 for connection with any suitable means, (not shown), actuated by hand or by power, to shift the grid back and forth continuously or at proper intervals. If desired the grid 70 can be provided with agitating fingers, as 21, Figs. 7 and 12, to agitate the fuel and so prevent arching over the grid.

Extending across the furnace below the hopper is a coal pusher plate 22, its rear edge 75 resting on the horizontal guide plate 19. On its underside the pusher plate is provided with racks 23, meshing with segmental gears 24, by which it can be reciprocated longitudinally of the furnace. The 80 gears named are fixed on a transverse shaft 25, which can be rocked continuously or at suitable intervals by any convenient mechanism for the purpose. Preferably this mechanism should be such as will permit 85 regulation of the speed of the pusher plate, and of the intervals between reciprocations thereof, within certain limits. Inasmuch as this mechanism is no part of the present invention it is deemed unnecessary to illustrate the same herein.

The fuel falling from the hopper 13 upon the guide plate 19 is pushed rearwardly off the latter (by the pusher plate 22) and upon the coking-plate 26, where the fuel, being 90 exposed to the heat of the fire, may undergo more or less coking. The guide-plate and the coking-plate are fixedly mounted on a transverse rockshaft 27. When the pusher plate is retracted, say about to the position 100 shown in Fig. 7, the shaft 27 can be rocked counterclockwise by any convenient means, not shown, thereby lifting the coking-plate for kindling or inspection of the fire and for slicing, raking, or any other work on the 105 fuel bed that may be required. The fire can also be observed through inspection doors 26^a, 26^b, in the sides of the setting. At its rear the coking-plate rests on the rear portion of a transverse dead-plate 28 which is 110 provided with a groove on its underside to fit down upon a transverse rib 29, thus permitting the dead-plate to swing up and down on the rib as a pivot as the front edge of the dead-plate resting on the first transverse series of grate-tops, rises and falls.

A scraper 30, of heavy sheet-metal bent to inverted V-shape, is mounted loosely on the pusher-plate 22 and in a transverse groove at the bottom of the hopper, to prevent fine bits of fuel from working out on the pusher plate.

The transverse rockshafts 31, Figs. 1, 2, 4, and 5, are mounted in the longitudinal side and center frames 33. The shafts are preferably all in the same plane, which is inclined downwardly from front to rear, or from left to right as seen in Fig. 1. Each shaft is provided with a plurality of arms or brackets 34, extending forwardly, that is, 125

toward the fuel-inlet end of the furnace, and supported by roller-bearings 32, Fig. 5, and on the brackets are mounted the transverse carrier-bars 35. The latter are substantially L-shaped in cross section, with their horizontal portions extending rearwardly and bolted to the brackets 34. The brackets and carrier-bars and the spacing of the rockshafts are preferably so proportioned that the forward portion of each carrier-bar will overlie the shaft immediately in front of the shaft by which the carrier-bar is supported, as will be clearly seen in Figs. 1 and 5.

Each shaft 31 (except the rearmost) also has loosely mounted on it, by means of roller bearings 36, Fig. 5, a plurality of collars 37, having downwardly extending actuating arms 38, and forwardly extending lifting lugs or fingers 39, and the carrier-bars 35 immediately above are provided with downwardly and forwardly extending fingers 40, resting on the lugs 39. As will readily be apparent from Fig. 5, the center of gravity of each carrier-bar and the associate brackets 34 and fingers 40 is in front of the shaft on which they are mounted, with the result that the fingers 40 rest by gravity on the lugs 39 and hence will follow the movements of the latter at all times.

The grate-tops 41 are preferably of elongated form, rounded off at their ends, and are provided at their front ends with downwardly open notches or recesses 42 to fit down loosely upon the upper edges 43 of the carrier-bars 35. The grate-tops are arranged side by side on the carrier-bars, forming a plurality of transverse series. The rear edge of the rearmost series, that is, the rear ends of the rearmost grate-tops, rest loosely on a transverse end frame 44, which forms the front edge of the passage 45 leading downwardly to the ashpit or hopper 46, while each series in front of the rearmost overlies the series immediately in rear, as clearly shown in Fig. 1. In other words, the grate-tops overlap from front to rear downwardly, but, as indicated in Fig. 2, they are preferably in longitudinal alinement. The grate-tops 41 are of sufficient depth to form a well defined series of steps, as clearly shown in Fig. 1.

As will be seen from the foregoing, my improved grate is composed, speaking generally, of a plurality of transverse grate-sections or units. In the present embodiment of the invention each section or unit of the stoking grate includes a suitably mounted carrier-bar 35 and a plurality of grate-tops 41 arranged side by side thereon.

For the purpose of actuating the arms 38 to raise the lugs 39 and so swing the carrier-bars 35 and grate-tops 41 upwardly and rearwardly, said arms are pivotally connected to a series of actuating links or bars 47, Figs.

1, 2, 3, 4 and 5, extending forwardly through

a horizontal series of slots in the furnace front-plate 48. At their front ends, outside of the front-plate, the links are provided with slidably adjustable crossheads 49, resting on roller-bearing guide-rollers 50, (Fig. 7) mounted on a transverse shaft 51 supported by forwardly extending brackets 52. In rear of the shaft 51 is a transverse cam-shaft 53 having two series of cams 54 for co-operation with the aforesaid crossheads to reciprocate the same and the links 47, thereby actuating the grate-top carrier-bars in the manner described. In the embodiment illustrated the primary edges of all the cams, that is the edges that first engage the crossheads, are in transverse alinement, but the cams of each series are of successively greater angular extent from the innermost cams (54¹) outwardly, as clearly shown in Fig. 7, so that all the crossheads will be advanced simultaneously but will be retracted in succession as the cams pass, thereby causing the grate-top carrier bars to swing forwardly and downwardly in succession from the front of the grate to the rear; it being understood, of course, that the inner crossheads (Fig. 2) are connected to the first shaft 31, the second crossheads to the next shaft 31, and so on.

The cams 54 of each series can be made as separate parts, fixed individually on the shaft in any convenient manner, but they are more conveniently made integral with each other in the form of a single casting. The cam-shaft is rotated continuously by any convenient and suitable mechanism, manual or power-driven, not shown, permitting the speed to be varied at will.

Above the links 47 and in rear of the crossheads 49 is a transverse shaft 55, equipped with two series of stroke-regulating arms or stops 56 (Figs. 1 and 7), one series for each series or set of crossheads, each stop being arranged to co-operate with, and limit the rearward movement of, its respective cross-head. The stops are successively longer from the innermost outwardly, toward the sides of the furnace, as clearly indicated in Fig. 7. Hence when the stops are swung from the position shown in Fig. 1 to that shown in Fig. 7, or to any intermediate position, the rearward (rightward) movements of the crossheads are successively less from the innermost crossheads outwardly, with the result that the upward and rearward movements of the grate-tops 41, by which movements the fuel is fed over the grate toward the rear or lower end of the same, are successively less from front to rear. It is clear that the extent of rearward movement of each crosshead, and hence of the corresponding transverse series of grate-tops, depends, other conditions being the same, upon the radial lengths of the stops from the axis of the shaft 55, and that these dimensions

can be varied as may be necessary or desirable to suit the conditions for which the particular furnace is designed. The stops of each series may be separate from each other 5 and secured individually on their shaft, but they are more conveniently made integral with each other in the form of a single casting, as shown in Fig. 6.

The shaft 55, carrying the stops 56, is adjusted to the proper position by any convenient mechanism, as for example a segmental worm-gear 57, Fig. 2, fixed on the shaft and meshing with a worm (not shown) on a short shaft 58, Fig. 2, which is mounted 15 in a bracket 59, on the shafts 53, 55, and is rotated by a handwheel 60. A worm and worm-gear mechanism is advantageous in that it not only enables accurate adjustment to be made by hand but also itself serves to 20 securely hold the shaft and stops in any position of adjustment.

When the stops 56 are in the position shown in Fig. 1 the crossheads are in transverse alinement. The revolving cams 54 will therefore engage and advance (toward the left) all the crossheads simultaneously and hence will raise and move rearwardly all 25 the grate-tops 41 simultaneously. If, however, the stops are in, say, the position shown 30 in Fig. 7, the innermost crossheads will be advanced first and will be moved the maximum distance, thereby raising and shifting rearwardly to the maximum extent the forward transverse series of grate-tops 41. The 35 next crossheads will be engaged by their respective cams a moment later and the extent of their forward (leftward) movement will be correspondingly less, with a corresponding effect upon the movement of their 40 respective series of grate-tops. In like manner the succeeding crossheads and grate-tops series are actuated so, also, in the return movements the innermost crossheads move rearwardly first, followed by the others in 45 succession. In short a wave of gradually diminishing vertical and horizontal components of motion may be said to traverse the successive series of grate-tops from the front of the furnace to the rear, thereby feeding 50 the fuel rearwardly over the grate at decreasing speed. In this way the consumption of fuel can be compensated for and the thickness of the fuel bed kept substantially uniform from front to rear. As will be 55 readily understood, the rate of decrease of the vertical and horizontal motion of the fuel-feeding "wave" can be varied at any time; whether there is a fire on the grate or not, by adjusting the stops 56 as already described.

An effect similar to that produced by the employment of the stops 56 as described can be obtained by placing the crossheads 49 successively farther out on the ends of the links, 65 as will be readily understood. This differ-

ential positioning of the crossheads is permitted by the use of set-screws, as 49 to fasten the crossheads on the links. The chief purpose of having the crossheads adjustable is to permit them to be lined up readily at 70 any time.

The grate-top carrier-bar 35 at the extreme front of the grate is not rocked by cams 54, and hence the only movement imparted to the extreme front series of grate-tops is a slight rocking, on the supporting edge of the carrier-bar, produced by the upward movement of the next series of grate-tops. This rocking of the extreme front series of grate-tops gives a slight swinging 75 movement in the dead plate 28, since the rear edge of the latter rests on said series of grate-tops, which movement is imparted to the coking-plate 26, the lower and rear edge of which rests on the rear of the dead plate. 80

Air for natural draft can be admitted to the air-chamber 61, Fig. 1, below the grate, by opening the inspection and cleaning doors 62 in the furnace front, Fig. 3. Air for mechanical draft is supplied through 90 ducts 63, at each side of the aforesaid doors, by means of a fan or blower, not shown.

The distribution of air through the grate to the burning fuel is a highly important factor in conjunction with the varying rate 95 of feed of the fuel over the grate. In the preferred embodiment of the invention the air that reaches the fuel bed from below comes through spaces between the grate-tops at the sides thereof. Preferably there are no 100 other air openings in the grate, and accordingly I prefer to have the grate-tops narrow in proportion to their length, so that air openings in the grate-tops themselves will not be needed to keep the temperature 105 of the grate-tops down to a safe point. In lieu of or in conjunction with bosses or projections (not shown) on the sides of the grate-tops to space the same apart I prefer to employ removable spacers 64 (Figs. 8, 9 110 and 11) between the grate-tops, in the form of inverted V-shaped members straddling the upper edges of the carrier-bars 35. These spacers may all be of the same width or transverse thickness as in Fig. 8, in 115 which case, as will be evident, the air spaces will be uniform throughout the grate; or they can be of different widths, for example as in Fig. 9, thus making corresponding differences in the areas of the air-openings. It 120 will therefore be seen that by using spacers of the proper widths the individual air-openings can be given any area desired, from zero up to any reasonable limit. So, also, by proper distribution of spacers of 125 different widths more air can be admitted at one part of the grate than another, thus giving any desired air-distribution. In order to insure proper positioning of the spacer on the carrier-bars, and to prevent 130

displacement of the spacers, especially in cleaning the grate, kindling the fire, or in raking, slicing, or other hand work on the fire, the grate-tops are provided with lateral recesses 65, at the points where they rest on the carrier-bars and the spacers are shaped to fit into these recesses, as clearly indicated in Figs. 5, 8 and 9.

A certain amount of air can be admitted above the coking-plate 26, Figs. 1 and 7, through a space 66, between the front of the roof 11 and the vertical rear wall of the fuel-hopper 13, which air will be pre-heated by heat reflected from the roof before mixing with the gases distilled from the fuel.

The invention is shown embodied in a furnace for heating a steam boiler (indicated by the water-tubes 66), but it is not limited to such use.

It is to be understood that the invention is not limited to the construction herein specifically illustrated and described, but can be embodied in other forms without departure from its spirit as defined by the appended claims.

I claim:

1. In an automatic furnace-grate, in combination, a plurality of transverse grate-sections or units, and mechanism for giving the same in succession from front to rear of the furnace a combined vertical and horizontal movement of reciprocation, whereby the fuel-bearing surface of the grate is given a wave-like motion traveling from front to rear.

2. In an automatic furnace-grate, in combination, a series of transverse shafts, a transverse carrier-bar mounted on each shaft and extending forwardly toward the next adjacent shaft, devices on each shaft for coöperating with the carrier-bar which is mounted on the next rearward shaft to swing the same on the axis of its shaft, and mechanism for actuating said devices.

3. In an automatic furnace-grate, in combination, a plurality of transverse grate-sections or units, and means for simultaneously and uniformly moving the grate sections or units from an initial position upwardly and toward the rear of the grate and causing the same to return to initial position in succession from front to rear of the grate.

4. In an automatic furnace-grate, in combination, a plurality of transverse grate-sections or units, pivotal supporting means for the grate-sections or units permitting the same to be moved by gravity to a lower and forward position, and mechanism for raising the grate-sections or units and moving the same in unison to an upper and rearward position and then releasing them in succession from front to rear of the grate to permit their return by gravity to their lower and forward position.

5. In an automatic furnace-grate, a grate-

section or unit comprising a transverse shaft, a plurality of brackets pivotally mounted on the shaft and extending forwardly therefrom, roller bearings for the brackets, a grate-top carrier-bar mounted on the brackets, and a plurality of grate-tops mounted on the carrier-bar.

6. In an automatic furnace-grate, a grate-section or unit comprising a transverse supporting shaft, a plurality of brackets mounted on the shaft and extending forwardly therefrom, a grate-top carrier-bar arranged in front of the shaft and fixed on the brackets, and a plurality of grate-tops mounted on the carrier-bar.

7. In an automatic furnace-grate, a grate-section or unit comprising a transverse supporting shaft, a plurality of brackets mounted on the shaft and extending forwardly therefrom, a grate-top carrier-bar arranged in front of the shaft and fixed on the brackets, a plurality of grate-tops mounted on the carrier-bar, and mechanism for swinging the carrier-bar about the axis of the shaft.

8. In an automatic furnace-grate, in combination, a plurality of transverse shafts, grate-top carrier-bars arranged to swing upon the axes of the shaft each carrier-bar being arranged adjacent to and above the shaft next in front of its own shaft, actuating fingers fixed on each carrier-bar and extending downwardly therefrom in front of the shafts over which the carrier-bars are arranged, actuating arms extending downwardly from the shafts and having lugs co-operating with the said fingers to raise the same and thereby swing the carrier-bars upwardly and rearwardly, and mechanism for rocking said arms on the axes of their shafts.

9. In an automatic furnace-grate, in combination, a plurality of transverse grate-sections or units; and mechanism for giving each grate-section a combined vertically and horizontally reciprocatory movement; said mechanism including a plurality of forwardly extending reciprocatory links connected to the grate-sections at their rear ends, and means for causing the links to be advanced simultaneously and retracted successively.

10. In an automatic furnace-grate, in combination, a plurality of transverse grate-sections, or units each capable of combined vertically and horizontally reciprocatory movement, a plurality of forwardly extending reciprocatory links connected at their rear ends with the respective grate-sections to actuate the same, and a transverse series of cams adapted to normally advance the links simultaneously and permit the same to be retracted in succession.

11. In an automatic furnace-grate, in combination, a plurality of transverse grate-sections or units each capable of combined ver-

- tically and horizontally reciprocatory movement, a plurality of forwardly extending reciprocatory links connected at their rear ends with the respective grate sections to actuate the same, a crosshead fixed on the forward end of each link, the crossheads being in transverse alinement when the links are in their rearmost positions, a series of cams to advance the crossheads and links having their primary edges in transverse alinement whereby to normally advance all the crossheads and links simultaneously, and a series of adjustable stroke-limiting stops adapted to restrict the rearward movement of the crossheads and links and hold the former successively farther from the primary edges of the cams whereby the links will be advanced, and the grate-sections actuated in succession when the cams are operated.
12. In an automatic furnace-grate, in combination, a plurality of transverse grate-sections or units each capable of combined vertically and horizontally reciprocatory movement, a plurality of forwardly extending reciprocatory links connected at their rear ends with the respective grate-sections to actuate the same, a crosshead fixed on the forward end of each link the crossheads being in transverse alinement when the links are in their rearmost positions, a plurality of cams of successively greater angular extent but having their primary edges in transverse alinement to normally engage and advance all the crossheads simultaneously, a series of stroke-limiting stops adapted to restrict the rearward movements of the crossheads and hold the same successively farther from the alined primary edges of the cams, and means for shifting the stops into and out of operative position.
13. In an automatic furnace-grate, in combination, a plurality of forwardly and rearwardly movable transverse grate-sections or units, a plurality of forwardly extending links connected at their rear ends to the respective grate-sections to actuate the same, means for causing the links to move forwardly and rearwardly, a shaft extending across the links at the front thereof, and a plurality of stroke-limiting stops fixed on the shaft to limit the rearward movements thereof.
14. In an automatic furnace-grate, in combination, a plurality of movable transverse grate-sections or units, a plurality of forwardly extending actuating links connected at their rear ends to the grate-sections, a plurality of crossheads fixed on the front ends of the links, means coöperating with the crossheads to cause the same and the links to move forwardly and rearwardly, and a plurality of guide-rollers under the crossheads to support the same.
15. In an automatic furnace grate, in combination, a plurality of transverse gate-sections or units capable of combined vertically and horizontally reciprocatory movement, a plurality of cams, and a plurality of links connected with the grate-sections to actuate the same and having means to coöperate with the cams for actuation thereby, said cams and means being adapted to move the links simultaneously in one direction and successively in the other direction.

In testimony whereof I affix my signature. 75
CHARLES A. HORN.
